Des. 195,713
Patented July 23, 1963

195,713

COIN OPERATED LIQUOR DISPENSER

George W. Bayers, Jr., 2314 Champa St., Denver, Colo.

Filed June 11, 1962, Ser. No. 70,520

Term of patent 14 years

(Cl. D2—3)

FIG. 1.

FIG. 2.

FIG. 3.

FIG. 3 is a view of one end thereof with the other end and back being flat and plain.

I claim:

The ornamental design for the coin operated liquor dispenser, as shown and described.
